UNITED STATES PATENT OFFICE.

HARRY J. CRINER, OF CLARINDA, IOWA, ASSIGNOR TO CLARINDA MANUFACTURING COMPANY, OF CLARINDA, IOWA, A CORPORATION OF IOWA.

ECCENTRIC DRIVING MECHANISM FOR POWER WASHING MACHINES.

Application filed September 10, 1925. Serial No. 55,497.

The object of this invention is to provide an improved driving mechanism, including a pair of oppositely arranged eccentrics, especially designed for use on power washing machines, transforming continuous rotary motion into oscillatory rotary motion, at reduced speed, with the aid of efficient speed reducing gearing.

A further object of this invention is to provide an improved flexible connector between eccentric straps and a follower device.

A further object of this invention is to provide an improved bearing means for a follower adapted for rotary oscillation and for sliding movement, together with means for adjusting said bearing laterally relative to the driving mechanism.

A further object of this invention is to provide an oil trough adjacent the bearing means of the follower.

A further object is to provide improved means of securing the eccentric straps around the eccentrics.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which,

Fig. 1 is a plan view, partly in section, of my device mounted on a washing machine, the covers of the gear housing and eccentric housing being partly removed. Fig. 2 is a sectional elevation of the same substantially on the line 2—2 of Fig. 1. Fig. 3 is a perspective view of the slide bearing member of the follower. Fig. 4 is a perspective view of the clamp used to secure the eccentric straps around the eccentrics.

In the construction and mounting of the mechanism as shown the numeral 10 designates a suitable support such as the tub of a washing machine, formed with a fixed cover member 11 and a movable cover member 12 adapted to overlie the major portion of the tub. A supporting plate 13 is mounted on and suitably fixed to the fixed cover member 11 and said plate is formed with an integral upstanding bearing bracket 14 between its ends. A driving shaft 15 is journaled for

rotation in the bearing bracket 14 and other bearing means hereinafter described, extends 55 longitudinally of and above the fixed cover member 11 and plate 13. Hinge members 16 and 17 are secured to the top of the movable cover member 12, extend upwardly and outwardly beyond the margin of said cover member and have bearings at their opposite ends on the driving shaft 15. Thus a pivotal connection of the cover member 12 to the support is established, the axis of articulation being removed laterally and vertically from the joint line between the cover members 11, 12. Any suitable means may be employed to limit outward movement of the cover member 12 on its hinged supports.

A motor 18 is mounted at the side of and near the top of the tub 10 by suitable brackets. This motor is connected to the rotatable shaft 15 by a train of spur gears which I have designated by the numeral 19. These gears are so designed and arranged 75 that the shaft 15 is relatively rotated at a much less speed than that of the motor. The numeral 20 designates a housing around the gears 19.

An eccentric housing 21, provided with a removable cover 22, is mounted transversely of the supporting plate 13 and extends past the center of the tub 10 and movable cover member 12, to which it is attached by means of bolts 23 or the like. The outer end portion of the eccentric housing is substantially circular in form, concentric with the shaft 15, free from attachment to the plate 13 or fixed cover member 11, and is movable around said shaft when the movable cover member 12 is moved through an arc to or from open position. The eccentric housing 21 is spaced from the gear housing 20 by a bearing sleeve 24 on the shaft 15. Loosely mounted on the shaft 15 within the housing 21 is an eccentric sleeve 25 on which are formed spaced parallel disks 26 and 27, arranged eccentrically of the shaft and oppositely to one another, in such manner that the fore eccentric of one disk corresponds to the back eccentric of the other. One end portion of the sleeve 25 extends through the housing 21, at that side opposite the gear housing 20 and is designed to engage clutch mechanism at times inside the clutch housing 28, said clutch member being

feathered on the shaft 15. This clutch mechanism may be placed in operative engagement with the sleeve 25, or out of operative engagement by manual oscillation of the lever 29.

A follower device is mounted at the center of the tub 10, comprising a dolly shaft 30, square in cross-section, and a dolly or agitator 31 thereon adapted to be positioned 10 within the tub when the cover member 12 is closed, said dolly shaft extending through a slot 32 in said cover member, and within the eccentric housing 21. Mounted within the eccentric housing 21, adjacent the inner 15 end thereof and resting thereon as shown in Fig. 2 is a bearing member 33. The numeral 34 designates a projection on this bearing member, pointing toward the shaft 15.

Extending vertically through this projection is a slot 35 designed to receive the bolt 36. This bolt extends also through a hole in the housing 21. The numeral 37 designates a set screw, screwed into the housing 21 and designed to engage the forward end 20 of the projection 34. By this arrangement when the bolt 36 is loosened the bearing member 33 may be moved a certain distance toward or from the shaft 15 when the set screw 37 is screwed in or out, the purpose of 25 which will be hereinafter understood. The bearing member 33 is held in any desired position by tightening the bolt 36 and screwing the set screw in the housing until it engages the projection. Journaled in and extending through the bearing member 33 is a 30 slide bearing member 38 of tubular form and designed for rotary oscillation, said slide bearing being formed with a vertical aperture fitted to and slidably receiving the dolly shaft 30 whereby said shaft is arranged for oscillation with and for vertical sliding movement relative to said bearing. The slide bearing 38 is formed near its upper end with a peripheral flange 39 or shoulder resting on the top of the bearing member 33. The slide bearing 38 projects through a slot 40 in the cover 22 of the eccentric housing and a head 41 is fixed to the upper end of the dolly shaft 30 and normally rests on the upper end of said slide bearing, but at times, as when the dolly device 31 is elevated by and rests upon a load in the tub, said head may be spaced above said slide bearing. The numeral 42 designates sprocket teeth arranged peripherally 45 on the slide bearing and located just above the peripheral flange 39. At the rear of the bearing member 33 or on the side opposite the projection 34 is an oil trough 43 communicating with the slide bearing 38.

The numeral 44 designates a sprocket chain which engages near its center the sprocket teeth on the slide bearing 38. This chain is pivotally connected at its ends to 50 the eccentric rods 45 and 46 located within

the housing 21 and said rods are formed with integral eccentric straps 47 and 48 embracing the eccentrics 26 and 27 respectively. The eccentric straps 47 and 48 have their free ends connected to the straps 45 and 46 by means of sleeves or clamps 49, (see Fig. 4) and bolts 50. These sleeves slip on the rods 45 and 46 and over the free ends of the eccentric straps and thereby hold those two members closely together. In each side 75 of these sleeves is a hole and through which extends the bolt 50. As the free ends of the eccentric straps and the eccentric rods are very close together a notch or portion of each must be cut away to allow the bolt 80 to pass through. By this arrangement not only are the sleeves securely clamped on the free ends of the eccentric straps and the rods, but the free ends of the eccentric straps are always held in proper position and are 85 prevented from pulling out of the sleeves, or tightening on the eccentrics and binding.

The chain may be tightened by moving the bearing member 33 forward or backward as heretofore explained.

The rods 45 and 46 and the straps 47 and 48 are preferably circular in cross-section and the eccentrics 26 and 27 are peripherally grooved to receive said straps. When the shaft 15 is operated and the member 25 is in 95 engagement with the clutch, alternating rotary motion is imparted to the slide bearing 38 and to the dolly shaft 30 and devices carried thereby by alternate draft in opposite directions on the chain 44, through the 100 oppositely arranged eccentrics 26 and 27, eccentric straps 47 and 48 and eccentric rods 45 and 46. The operation of the dolly devices in this manner is very quiet as there are no intermeshing gears between the driving shaft and dolly shaft, few places where friction can occur, and a small number of 105 movable parts.

The moving parts are all enclosed, and ample provision is made for lubricating 110 them. The circular outer end portion of the eccentric housing 21 forms a reservoir for lubricant, into which the eccentrics 26 and 27 dip as they are rotated.

I claim as my invention—

1. A driving mechanism, comprising a support, a driving member journaled on said support and formed with oppositely arranged eccentrics, a housing enclosing said eccentrics and extending at right angles to 120 said driving member, a bearing member mounted in said housing, a slide bearing arranged for rotary oscillation in said bearing member and formed with a peripheral flange resting thereon, a follower shaft arranged 125 for sliding movement in and oscillation with said slide bearing, sprocket teeth arranged peripherally on said slide bearing immediately above said flange, a chain engaging said teeth near its center, and driving con- 130

nections between the ends of said chain and the respective eccentrics, for the purposes stated.

2. A driving mechanism, comprising a support, a driving member journaled on said support and formed with oppositely arranged eccentrics, a housing enclosing said eccentrics and extending at right angles to said driving member, a bearing member 10 mounted in said housing, a slide bearing arranged for rotary oscillation in said bearing member and having a peripheral flange resting thereon, a follower shaft arranged for sliding movement in and oscillation with

said slide bearing, sprocket teeth on said 15 slide bearing immediately above said flange, a chain engaging said teeth near its center and adapted for contact with said flange, driving connections between the ends of said chain and the respective eccentrics, and an 20 oil trough on and extending laterally from said bearing member and communicating with said slide bearing, for the purposes stated.

Signed at Clarinda, in the county of Page 25 and State of Iowa, this 11th day of May, 1925.

HARRY J. CRINER.
